DESIGN FOR A FUR COLLAR

Harry Raiffe, New York, N. Y.

Application June 19, 1941, Serial No. 101,542

Term of patent 3½ years

To all whom it may concern:

Be it known that I, Harry Raiffe, a citizen of the United States, residing in New York city, in the county of Bronx and State of New York, have invented a new, original, and ornamental Design for Fur Collars, of which the following is a specification, reference being had to the accompanying drawing, forming part thereof, in which—

I claim:

The ornamental design for a fur collar, as shown.

HARRY RAIFFE.
